VALVE ASSEMBLY

Thomas E. Crockett, Corpus Christi, Tex., assignor, by mesne assignments, to Crockett Valve Corporation, Los Angeles, Calif., a corporation of California

Application October 18, 1949, Serial No. 122,053

2 Claims. (Cl. 137—413)

1

My invention relates to float controlled valves. An important object of the invention is to provide a valve of the above mentioned character which is well adapted for use in connection with flush tanks, although it is not restricted to this use and may be used for other purposes.

A further object of the invention is to provide a valve of the above mentioned character having a piston-valve moved by unbalanced pressures upon its opposite ends, and which is reliable in operation, of highly simplified construction, produces the minimum noise in operation, and quickly discharges the water when the piston-valve is unseated.

A further object of the invention is to provide a pilot valve which controls the pressure upon one side of the piston-valve and which is seated by the flow of water passed about the same, and unseated by the descent of the float.

Other objects and advantages of the invention will be apparent during the course of the following description.

In the accompanying drawings, forming a part of this application, and in which like numerals are employed to designate like parts throughout the same,

Figure 1 is a side elevation of a flush tank and float controlled valve embodying my invention, parts of the tank being broken away.

Figure 2 is a central vertical longitudinal section through the float controlled valve, upon an enlarged scale, the pilot-valve being seated,

Figure 3 is a horizontal section taken on line 3—3 of Figure 2,

Figure 4 is a similar view taken on line 4—4 of Figure 2,

Figure 5 is a similar view taken on line 5—5 of Figure 2,

Figure 6 is a similar view taken on line 6—6 of Figure 2, and,

Figure 7 is a central vertical section through the top end of the valve casing, showing the pilot-valve in the lowered unseated position.

In the drawings, where for the purpose of illustration is shown a preferred embodiment of my invention, the numeral 10 designates a flush tank having a bottom 11. Extending to the bottom 10 is a water inlet pipe 12 through which water is supplied at main pressure, and a water outlet pipe 12' through which water is flushed from the tank in the well known manner. The pipe 12 is connected with a vertical pipe 13 arranged within the tank 10.

The valve assembly comprises a cylindrical casing 14, having its top open and provided with

5 a bottom 15. The bottom 15 is provided with a sleeve or coupling 16, having screw threaded engagement with the upper end of the vertical pipe 13. The bottom 15 has an annular group of discharge openings 17, surrounding the sleeve or coupling 16. The casing 14 has a considerably larger diameter than the pipe 13, whereby the valve assembly has a large capacity for the discharge of the water, which will permit of the rapid filling of the flush tank. Arranged above the casing 14 is a cap or head 18, having a depending annular flange 19, having screw-threaded engagement with the upper open end of the casing 14, to close the same. Formed integral with this cap is a vertical casing extension 20, which is cylindrical, as shown. The casing extension has a top 20' provided with radial ports 21, leading to a vertical bore 22, which leads to a downwardly flaring valve seat 23. The top 20' has a vertical opening 24.

10 Mounted to slide within the casing 14 is a piston-valve 25, provided at its bottom end with an annular groove 26, receiving a packing ring 27, adapted to engage upon the seat 28 of the bottom 15. The piston-valve is provided in its side with a horizontal annular groove 29, receiving a packing ring 30, engaging the side of the casing 14. The packing ring 27 is disposed outwardly of and near a lower large opening 31, which is cylindrical and leads to a large cylindrical opening 32 formed in the bottom 15. The opening 32 is in free communication with the interior of the pipe 13, as shown. A cylindrical recess 33 is formed in the top of the piston valve 25 and is concentric with the opening 31, leads into this opening and has a larger diameter than the same, forming a shoulder 34. Mounted within the recess 33 is a horizontal plate 35, having a depending annular flange 36. Attached to the lower end of the flange 36 is a strainer element 37. Mounted upon the top of the plate 35 is a flexible flap valve 38 held in place by a rivet 39. This flap valve covers a reduced opening 40 formed in the plate. The flap valve unseats upwardly. The plate 35 and flange 36 are held within the recess 33 by any suitable means, such as a press fit, or they may be welded or otherwise secured to the piston valve 25.

15 Mounted to reciprocate vertically within the casing extension 20 is a pilot-valve element 41. This pilot-valve element 41 has an upper tapered portion 42 to engage the valve seat 23 and a lower portion 44, having flats, providing passages for the upward flow of the water. Rigidly secured to the valve element 41 is a stem 45 sliding within

the vertical opening 24 and projecting above the top 20', as shown. The exterior diameter of the stem 45 is considerably less than the internal diameter of the bore 22, thereby providing a space for the upward flow of the water to the ports 21; when the pilot valve element is unseated. The area for the escape of water through the bore 22 is considerably greater than the area of the opening 40, whereby the water pressure is greater upon the lower end of the pilot-valve. The down movement of the pilot-valve element is limited by a horizontal pin 46, secured to the casing extension 20, as shown.

A vertical bracket 47 is rigidly secured to the cap or head 18 and has a lever 48 pivoted thereto, as shown at 49. A float 50 is secured to the free end of the vertically swinging lever 48.

A sleeve 51 is secured to the casing 14 and is submerged in the water in the tank 10. This sleeve receives the water from the openings 17 and the water discharges from the lower end of the casing 51, eliminating the noise.

The operation of the device is as follows:

When the tank 10 is filled with water to the desired elevation, the float 50 is raised and the lever 48 swung upwardly. The pilot-valve 41 now engages the seat 23 and the escape of water through the bore 22 is prevented. The flap valve 38 is now seated to close the opening 39, and water cannot flow back into the pipe 12 from the tank. The flap valve 38 may be omitted, and the device will operate. The purpose of the flap valve is to prevent the backflow of water into the pipe 12, as stated. The water pressure at the bottom and top ends of the piston-valve 25 is now the same, but the increased area at the top of the piston-valve securely holds the piston-valve seated. When the water is flushed from the tank through the pipe 12', the level of the water rapidly descends and the float 50 and lever 48 move downwardly. The weight of the descending lever and float is now sufficient to overcome the upward water pressure upon the pilot valve 41, which is unseated and thereby quickly moves to the lowered open position, Figure 7. The water above the piston-valve 25 is now free to discharge upwardly through the casing extension 20, about the pilot-valve 41, and through the ports 21. The pressure is therefore reduced at the top of the piston-valve and the pressure beneath the piston-valve moves the piston valve upwardly and unseats the same. As soon as the piston-valve disengages the seat 28, the water discharges through the openings 17 and enters the tank. When the piston-valve moves upwardly, due to the reduction of pressure above the top of the piston-valve, the water also passes upwardly through the reduced opening 40 and retains the space above the piston-valve and the casing extension filled with water. The water rapidly discharges from the flush tank through the pipe 12', as is well known. As soon as the discharge of water from the tank 10 through the pipe 12' is stopped, due to the closing of the usual flush valve, the water discharging through the openings 17 begins to fill the flush tank and the float 50 and lever 48 begin to rise. As soon as the lever 48 has reached the uppermost position, defined by the selected elevation of the water within the tank 10, the weight of the lever and float is taken from the stem 45. The water continues to travel upwardly through the casing extension 20 and bore 22 and this upward travel of the water within the casing extension 20 moves the pilot-valve 41 upwardly and

returns it to its seat. As soon as this occurs, the pressure increases upon the top of the piston-valve 25 and this increased pressure moves the piston valve 25 downwardly so that it engages the seat 28 and the flow of water through the openings 17 is cut off. The flap valve 38 again closes, and the piston valve will remain seated until the pilot valve is again unseated.

It is to be understood that the form of my invention herewith shown and described is to be taken as a preferred embodiment of the same, and that various changes in the shape, size and arrangement of parts may be resorted to without departing from the spirit of the invention or the scope of the subjoined claims.

Having thus described my invention, I claim:

1. A float controlled valve comprising a casing provided with a main bore and having its top open and including a bottom wall, said bottom wall being provided with a relatively large central opening and a plurality of discharge openings surrounding the central opening and spaced radially therefrom, the upper surface of the bottom wall between the central opening and said discharge openings constituting a valve seat, a reduced depending sleeve formed integral with the bottom wall inwardly of the discharge openings and having a screw threaded opening to receive the upper screw threaded end of an inlet pipe, the screw threaded opening leading into said central opening of the bottom wall, a main piston valve mounted within the main bore of the casing for reciprocation and having an opening in its lower end which is substantially coextensive with said central opening of the bottom wall and in communication therewith, the main piston valve having an enlarged recess in its upper end forming a lateral shoulder, a sleeve mounted within the enlarged recess of the piston valve and having its lower end seated upon the lateral shoulder and including a top end having a restricted port, a strainer secured to the lower end of the last named sleeve and extending over said opening of the piston valve, an upwardly opening flap valve secured to the top of the last named sleeve and adapted to cover the reduced port, a cap removably mounted upon the upper end of the casing and having a bore leading into the main bore of the casing and a discharge port leading from the bore of the cap, a pilot valve mounted within the bore of the cap for reciprocation and adapted to cover and uncover the discharge port of the cap, a vertically movable float lever connected with the pilot valve to urge the same downwardly in the bore of the cap, and a float secured to the float lever.

2. A float control valve comprising a casing provided with a main bore and having its top open and including a bottom wall, said bottom wall being provided with a relatively large central opening and a plurality of discharge openings arranged in a group surrounding the central opening and spaced radially therefrom, the upper surface of the bottom wall between the central opening and said discharge openings forming a valve seat, a reduced depending sleeve formed integral with the bottom wall radially inwardly of the discharge openings and having a screw threaded opening to receive the upper screw threaded end of an inlet pipe, the screw threaded opening leading into the central opening of the bottom wall, a main piston valve mounted within the main bore of the casing for reciprocation and having a reduced opening in communication with the main bore of the casing above and be-

low the main piston valve, a cap removably mounted upon the upper open end of the casing for covering the same and having a main bore and an upper end provided with a reduced bore leading into the main bore of the cap, a reciprocatory pilot valve mounted within the main bore of the cap for covering and uncovering the reduced bore thereof and including a reduced stem extending through the reduced bore of the cap and above the top of the cap, a fixed abutment mounted within the main bore of the cap for engagement with the pilot valve to limit its downward movement, a lever pivotally mounted above the casing for engagement with the stem of the pilot valve to move the pilot valve downwardly, and a float secured to the lever. 15
